BROOCH ASSEMBLAGE

Marcel Boucher, Eltingville, N. Y.

Application November 23, 1936, Serial No. 112,323

8 Claims. (Cl. 63—1)

This invention relates to a brooch assemblage, in which two ornamental clips, each complete in itself and suitable for individual use, are detachably connected and combined to form a brooch. 5 As a brooch assemblage of this character is well known in the art, the present invention resides in the means employed to connect the clips in assembled relation.

The object of the invention may be stated in 10 terms of the commercial requirements of the article. That is, first and most important, security in the assembly, to insure against the brooch members working loose or becoming otherwise accidentally disengaged and lost, and second, a 15 simple, easy and quick operation in assembling and disassembling the brooch members, so that there will be instant understanding by users and no skill or experience required.

With these requirements in mind, I have devised a three-member assemblage, consisting of 20 twin clips and a plate, carrying the brooch-attaching pin. The assemblage, as designed, is independent of the hinged back jaws of the clips, which come into use only when the members are 25 disassembled, to permit individual use of the clips and they then serve as the attaching means for fastening the clips to the garment of the wearer, in the usual and customary manner.

The present invention is limited to cooperative 30 relation between the brooch pin-carrying plate and the underside formation of the front jaws of the clips and is made effective without in any way obstructing or otherwise interfering with the free use of the hinged back jaws in the performance of their function in fastening the clips, when used individually on the garment of the wearer.

The plate carrying the brooch-attaching pin, is formed as a separate unit, to permit complete 40 detachment thereof from the clips, which latter, detached from the connecting pin-plate, become simple hinged jaw members, free of any and all complication and ready for instant use.

In addition to carrying the brooch-attaching 45 pin, the pin-plate is shaped to bridge or overlap the abutting inner ends of the front jaws of the clips, when the members are assembled, and so securely brace the same against "wobbling" or independent movement, such as might be brought 50 about by idle handling on the part of the wearer.

The pin-plate is furthermore provided with extensions shaped to serve as elements of spring latches, by which the twin clips are secured in assembled relation.

55 The clips carry the cooperating latch elements

on the underside of the front jaws and are so shaped and arranged as to permit the pin-plate extensions to slidably enter into engagement with the same. The engagement between the latch elements is eased and facilitated by giving the pin-plate extensions cam-like terminals which act to gradually position the elements preparatory to actual engagement. 5

A construction suitable for carrying my invention into effect, is illustrated in the accompanying drawing but I do not wish to be understood as intending, by such showing, to limit myself to the same, as various changes may be made in both the form and details, without departing from the spirit and scope of the invention as 10 outlined in the appended claims.

In the drawing—

Fig. 1 is a front view showing the assemblage of twin clips in brooch-forming relation, the exposed faces of the clips, it will be understood, 20 are intended to carry suitable ornamentation.

Fig. 2 is a rear view of the same assemblage and, for clearness of illustration, the hinged back jaw of the left hand clip has been omitted but its form and mounting will be evident from the 25 back jaw of the right hand clip, as clips are exact duplicates throughout and interchangeable one for the other.

Fig. 3 is an edge view of the assemblage, in which, as in Fig. 2, the hinged back jaw of the 30 left hand clip has been omitted, and

Fig. 4 is a detail perspective view, showing one 35 of the latch element extensions of the pin-plate, about to enter the guide and engage the resilient formation of the front jaw of the clip, the aforesaid guide and resilient formation being shown separated from their permanent location on the underside of the front jaw, to more clearly illustrate the construction and operation of the parts shown.

Referring now to the drawing, the twin clips of the assemblage are shown at 1, 1, each of which has an ornamental front jaw 2 and a back jaw 3, hinged thereto, as indicated at 4. The back jaw is provided with a resilient formation at 5, 45 which cooperates with a lug 6, projecting from the underside of the front jaw, to yieldingly hold the back jaw open or closed in a manner well known in the art. Spurs 7, 7 on the inner side 50 of the back jaw, are designed to pierce the material of the garment of the wearer, as the clip jaws are closed and secure the clip in position, when the latter is used individually as an ornament.

In the lug 6 of each clip, a rectangular opening 55

8, is formed to serve as a guide for an entering pin-plate extension, hereinafter described and beyond and in line with the guide, there is a resilient formation 9, designed to act as one element of a spring latch, the other element of which is formed in part with the pin-plate above referred to.

Preferably, the lugs for the back jaw hinge 4, the apertured lug 6-8 and the resilient formation 9 of the latch, are stamped out and shaped up from one piece of sheet metal, which is soldered to the underside of the front jaw and becomes, in effect, an integral part of it.

As will be seen from the drawing and as the foregoing description makes clear, the clips are of identical, symmetrical construction and may therefore be interchangeably used in the assemblage, having no right and left hand peculiarity.

The third member of the assemblage is the pin-carrying plate, indicated at 10. The pin 11, hinged to the plate at 12, and having its free pointed end held by a retaining catch 13, mounted on the plate, is of the usual form and mounting well known in the art.

Extending outward at right angles and centrally from the pin-carrying section of the plate 10, there is a section 14, having an enlarged end 15. This section is designed to bridge or overlap the abutting ends of the front jaws of the clips, 30 when in assembled relation, to prevent independent movement of the clips, as previously pointed out.

Extending outward in opposite directions from a mid point of the section 14 and in parallel relation to the pin-carrying section of the plate 10, there are two sections 16, 16, the cross sectional form of which corresponds to the rectangular guide openings 8, 8 in the lugs 6, 6 of the front jaw. These extensions 16, 16 of the pin-plate 40 terminate in bevelled ends 17, 17, which are designed, as either extension is slidably entered in either guide opening 8, to ride under and cam up the resilient latch element 9 of the front jaw, which is located just beyond the guide. Thus 45 cammed up, the latch element 9, is positioned for engagement with its cooperating latch element of the pin-plate, as the plate is pushed home. The pin-plate latch element, as shown, is in the form of a rectangular aperture 18, cut in each of the plate extensions 16, 16.

Constructed as described, the members of the assemblage may be said to be secured in interlatching, rather than interlocking relation, as the latch elements are shaped to yield and ride into engagement, as the members are pressed together and to similarly yield and ride out of engagement, as the members are pulled apart.

As the operation and many important advantages of the invention will be apparent from the foregoing, it will not be necessary to further describe the same.

Having described my invention, I claim:

1. A brooch assemblage comprising twin clips each having an ornamental front jaw and a back jaw hinged thereto, the front jaws being provided on their underside with suitable guides and a resilient formation in line with but separate and independent of each of the guides, and a pin-carrying plate slidable in the aforesaid guides into interlatching engagement with the resilient formations of the front jaws to secure the clips in assembled relation to form a brooch.

2. A brooch assemblage comprising twin clips each having an ornamental front jaw and a back jaw hinged thereto, the front jaws being pro-

vided on their underside as an integral part thereof with suitable guides and a resilient formation in line with but separate and independent of each of the guides, and a rigid, non-resilient pin-carrying plate slidable in the aforesaid guides into interlatching engagement with the resilient formations of the front jaws to secure the clips in assembled relation to form a brooch. 5

3. A brooch assemblage comprising twin clips each having an ornamental front jaw and a back jaw hinged thereto, the front jaws being provided on their underside with suitable guides and a resilient formation in line with but spaced apart from each of the guides, and a pin-carrying plate carrying latch elements, the said pin-plate being slidable in the aforesaid guides to move its latch elements into engaging relation with the resilient formations of the front jaws to secure the clips together to form a brooch. 10 15

4. A brooch assemblage comprising twin clips each having an ornamental front jaw and a back jaw hinged thereto, the front jaws being provided on their underside with suitable guides and a resilient formation in line with but spaced apart from each of the guides, and a rigid, non-resilient pin-carrying plate carrying integrally formed latch elements, the said pin-plate being slidable in the aforesaid guides to move its latch elements into engaging relation with the resilient formations of the front jaws to secure the 20 25 30 35 clips together to form a brooch.

5. A brooch assemblage comprising twin clips each having an ornamental front jaw and a back jaw hinged thereto, the front jaws being provided on their underside with suitable guides and resilient formations in line with the guides, and a pin-carrying plate slidable in the aforesaid guides and having cam-like terminals and a latch element in the rear of each terminal, the cam-like terminals operating to position the 40 45 50 resilient formations of the front jaws for entrance and engagement of the latch elements therewith to secure the clips in assembled relation.

6. A brooch assemblage comprising twin clips each having an ornamental front jaw and a back jaw hinged thereto, the front jaws being provided on their underside with suitable guides and a resilient latch member in line with each of the guides, the said latch members being limited to movement in a plane perpendicular to the underside of the front jaw, and a pin-carrying plate slidable in the aforesaid guides into interlatching engagement with the resilient latch members of the front jaw to secure the clips in assembled 55 60 65 70 75 relation.

7. A brooch assemblage comprising twin clips each having an ornamental front jaw and a back jaw hinged thereto, the front jaws being provided on their underside with suitable guides and a resilient latch member in line with each of the guides, the said latch members being limited to movement in a plane perpendicular to the underside of the front jaws, and a pin-carrying plate slidable in the aforesaid guides and having cam-like terminals and a latch element in the rear of each terminal, the cam-like terminals operating to raise the resilient latch members of the front jaws for entrance and engagement therewith of the latch member of the pin-plate to secure the 70 75 80 85 90 clips together.

8. A brooch assemblage comprising twin clips each having an ornamental front jaw and a back jaw hinged thereto, the front jaws being provided on their underside with suitable guides and 75

5 a resilient latch member formed as a bent-over portion of each guide, the said latch members being limited to up and down movement relative to the underside of the front jaws, and a pin-carrying plate slideable in the aforesaid guides and having cam-like terminals and an aperture in the rear of each terminal, the cam-like ter-

minals operating to raise the resilient latch members of the front jaw preparatory to such latch members entering into engagement with the apertures of the pin-carrying plate to secure the clips together.

5
